SPACE DISCHARGE DEVICE

Carl F. Miller, Emporium, Pa., assignor to Hy-grade Sylvania Corporation, Salem, Mass., a corporation of Massachusetts

Application October 22, 1934, Serial No. 749,344

6 Claims. (Cl. 250—27.5)

This invention relates to devices such as lamps, tubes and electron discharge devices and with particularity to improvements in electrode supporting and/or spacing means.

5 In certain types of devices, for example, in electron discharge tubes, it is highly important that the several electrodes be maintained in proper spaced relation with respect to one another and also with respect to the wall of the enclosing envelope.

Accordingly one of the principal objects of this invention is to provide a novel form of spacer whereby the electrodes of a radio tube, lamp or similar device can be maintained in predetermined

15 fixed spatial relations with respect to the enclosing envelope and with respect to one another.

It has been proposed heretofore to provide the electrode assembly or mount of a radio tube or the like with a disc or similar member which is adapted to bear against the inner wall of the tube envelope to steady the electrode assembly. For example, one known type of spacer for this purpose consists of a disc of mica or similar insulating material provided with a series of aligned perforations adapted to register with the several electrode support posts, said member having edge projections to engage the wall of the envelope. This type of spacer has the disadvantage however that since it is assembled in end-on relation and over the ends of the supporting posts, it is not possible for the person assembling the device to view conveniently the interelectrode spacing, and in the case of tubes having a large 30 number of electrodes each electrode support post must be manually and individually aligned with its corresponding perforation in the spacer member. Because of the end-on assembly method necessitated by this prior type of spacer disc, unless the various electrode support posts are held in the proper spaced relation during the assembly of the spacer, much time is consumed in effecting the proper assembly of the spacer. Furthermore any non-uniformity of spacing between the 35 various posts as compared with the disc perforations, may require a forcing of the disc into position with the possibility of chipping the edges of one or more of the perforations, thus introducing a source of non-uniformity in the finished 40 tube.

Accordingly another object of this invention is to provide a bi-part spacer member which may be assembled in such a way that during the assembly operation the interior spacing of the electrodes 45 may be clearly observed.

A feature of the invention relates to a bi-part spacer member which is capable of being assembled in a motion which is substantially perpendicular to the longitudinal axis of the electrode assembly.

Another feature relates to a bi-part spacer member having cooperating notches in opposing edges to define a plurality of perforations for receiving and spacing the support posts of an electrode assembly.

10 A further feature relates to a spacer member wherein the leakage path between the several electrode posts passing therethrough is materially reduced.

A still further feature relates to a spacer member 15 having a plurality of substantially circular perforations adapted to receive electrode support posts and a rectangular perforation to receive an electron-emitting cathode member.

A still further feature relates to a spacer member 20 which is capable of being assembled so that it is positioned between, and supports the turns of a helically wound electrode or similar member.

Other features and advantages not specifically 25 enumerated will be apparent after a consideration of the following detailed descriptions and the appended claims.

While the invention will be described herein as embodied in one known type of discharge device, namely, a dome type radio tube, it will be understood that this is done merely for purposes of explanation and not by way of limitation.

Accordingly in the drawing, Fig. 1 is a top plan view, partly in section, of a tube embodying features of the invention.

30 Fig. 2 is a partial sectional view of a tube such as is partly illustrated in Fig. 1.

Fig. 3 is an explanatory diagram showing the manner in which the bi-part spacer member is assembled.

Fig. 4 is a detailed sectional view of the arrangement of Fig. 1 along the line 4—4 but with certain of the parts omitted for clarity.

Fig. 5 shows an alternative arrangement where in the spacer member intersects one of the electrodes between adjacent turns.

Referring more particularly to Figs. 1 and 2, the numeral 1 represents an enclosing envelope such as is ordinarily employed in radio tubes, lamps or similar devices. Preferably, although 50 not necessarily, the envelope 1 terminates at its upper end in a portion 2 of reduced diameter, this portion being provided, if necessary, with a metallic connection cap 3 of known construction. The envelope 1 may be provided at its lower end 55

with a mount including an electrode assembly and a reentrant stem terminating in a press (not shown) wherein the various lead-in and electrode support wires are sealed. As shown in Figs. 1 to 3 of the drawing the electrode assembly of the mount may comprise a central tubular or cylindrical cathode member 4 and a plurality of concentric electrodes 5, 6, 7, 8. Thus for example, the electrodes 5, 6 and 7 may consist of wire wound, or other foraminous structures capable of acting as grids, while the electrode 8 may consist of a solid or perforated plate adapted to act as an anode. Each of the electrodes 5, 6, 7 and 8 may be provided with a pair of vertical uprights or supporting posts. Thus the grid 5 is wound around or is supported by the posts 9, 10; the grid 6 is supported by posts 11, 12; grid 7 is supported by posts 13, 14; while the plate 8 is supported by posts 15, 16. Preferably the various electrode supporting posts extend slightly beyond the ends of the associated electrodes as clearly shown in Fig. 2 of the drawing.

For the purpose of spacing the several electrodes from one another there is provided, in accordance with the invention, a bi-part spacer member comprising the part 17 and the part 18. Parts 17 and 18 may be made of any suitable material preferably an insulating material such as mica or the like. As shown clearly in Figs. 1 and 3, the part 17 is provided with oppositely extending arms 19, 20 and a third arm 21 extending at right angles to arms 19 and 20. Each of the said arms is provided with smaller projections or teeth 22 which are adapted to engage the inner wall of the portion 2 of the envelope as shown clearly in Fig. 1 of the drawing. The arms 19 and 20 are provided with two circular perforations adapted to register with and fit over the plate support posts 15, 16. The said perforations in member 17 are in alignment with the edge 23 which in turn is provided with a series of aligned notches adapted to register with corresponding posts 9 to 14 inclusive. The said edge is also provided with a V-shaped notch adapted to register with the tubular cathode member 4. Preferably the notches registering with the support wires 9 to 14 are semi-circular although if desired these notches may be V-shaped.

The part 18 of the bi-part spacer member is likewise provided with a pair of perforations adapted to register with the posts 15 and 16 and the edge 24 is also provided with a series of semi-circular notches 25, 26, 27, 28, 29, 30, and with a central V-shaped notch 31. The notches in member 18 are so arranged that when the said member is assembled as shown in Fig. 1 the cooperating notches in the edges 23 and 24 define a central rectangular perforation to receive the cathode member 4 and a plurality of sets of circular perforations to receive the posts 9 to 14. Preferably the V-notches are so designed that when the parts 17 and 18 are assembled they define a square opening having a width substantially equal to the diameter of the cathode member 4, so that the said cathode member is supported at four points around its periphery.

The manner of assembly of the spacer member is believed to be obvious from the foregoing description. Suffice it to say that the member 17 is first placed in position with the outer perforations engaging plate support posts 15 and 16 and if desired the said member 17 may rest upon and be supported by the upper edge of the cylindrical electrode 8 as shown more clearly in Fig. 2. Likewise the member 18 is then assembled over the

post 15 as indicated in Fig. 3 and the said member is then swung around until the notches in the edge 24 engage the associated electrode support posts whereupon the tongue 31a may be slipped over the post 16. With the parts thus assembled, small metal cross pieces 32, 33 may be welded to the posts 15, 16 to fasten the spacer members against vertical movement.

As will be noticed from the showing of Fig. 4, the members 17 and 18 when assembled are not in the same plane so that the effective length of the leakage path between the several electrode support posts is correspondingly increased. The electrode assembly having the spacer means fastened thereto is then positioned within the envelope 1, so that the teeth 22 flexibly engage the wall portion 2. Consequently the electrode assembly is thus supported against tilting movement on opposite diameters.

If desired the members 17 and 18 in addition to supporting the electrode assembly against tilting movement with respect to the envelope 1 may also be used to support one or more of the grid electrodes 5, 6 and 7. Thus as shown in Fig. 5 the electrode 5 consisting of a wire 34 helically wound around the support posts 9 and 10 is slightly longer than the anode 8 so that when the members 17 and 18 are assembled they intersect the grid electrode between two adjacent turns. By this arrangement therefore, the members 17 and 18 support the grid electrode against tilting movement in the manner described in connection with Figs. 1 to 3 and at the same time the said grid is supported against vertical movement by reason of the interlocking arrangement between the members 17 and 18 and the associated grid turns.

While specific shapes and arrangements of the members 17 and 18 have been disclosed herein, it will be understood that the invention is not limited thereto. For example, where the anti-tilting effect is not desired the arms 19, 20 and 21 may be omitted in which event the bi-part members 17 and 18 serve merely to space the various electrodes from one another. Furthermore while one specific manner of engaging the envelope with the spacer is shown, various modifications and changes may be made therein without departing from the spirit and scope of the invention.

The foregoing arrangements provide means for supporting the elements of a tube so that there is a minimum of microphonic noise or electrical disturbance resulting from the tight-fit that is obtained between the mica and the various support posts. Furthermore the chances of the elements of the electrode assembly rattling or being mechanically jarred are materially reduced.

What I claim is:

1. An electron discharge device having an envelope, a mount within said envelope and comprising a plurality of electrodes having side posts, an insulating spacer having an edge provided with a plurality of slots, said side posts being received in said slots to space said electrodes in fixed relation with respect to each other and an insulating member cooperating with said spacer for closing the ends of said slots to lock said side posts in said slots.

2. An electron discharge device having an envelope, a mount within said envelope and comprising a plurality of electrodes having side posts, an insulating spacer having an edge provided with slots for receiving the ends of said side posts, a second insulating spacer having an edge pro-

vided with slots in registry with the slots in said first spacer, said spacers being positioned to lock said side posts between said spacers within said slots.

5. An electron discharge device having an envelope, a mount within said envelope comprising a plurality of electrodes having side posts with their ends in alignment, a spacer positioned on one side of said side posts and provided with 10 apertures in which the end side posts are received and a straight edge having slots in which the rest of the side posts are received, a second spacer positioned on the other side of said side posts above said first spacer and in contact therewith and having apertures in which the end side posts are received and a straight edge having slots in 15 registry with the slots on said first spacer in which the rest of the side posts are received, said spacers being secured to said end side posts to lock the side posts in the slots between said spacers.

20. 4. A device of the character described comprising-

ing an electrode assembly said assembly including a pair of electrodes, and means for spacing said electrodes comprising a pair of separable insulator members having registering notches in their opposed edges said notches engaging corresponding projections on said electrodes.

5. A device according to claim 4 in which certain of said registering notches define a circular opening and others of said notches define a 10 rectangular opening.

6. A device of the character described comprising a tubular cathode member, an electrode having a supporting post, means to space said cathode from said electrode comprising a bi-part insulator member the opposing edges of each part 15 of said member being provided with registering notches one set of notches defining a circular opening to receive said post, and the other set defining a rectangular opening to receive said cathode member.

20. CARL F. MILLER.
